UNITED STATES PATENT OFFICE.

GEORGE J. ABDELNOUR, OF NEW YORK, N. Y.

DESIGN FOR AN EMBROIDERED TEXTILE FABRIC.

Application filed March 3, 1926. Serial No. 16,758. Term of patent 3½ years.

To all whom it may concern:

Be it known that I, GEORGE J. ABDELNOUR, a citizen of the United States, residing at New York city, in the county of New York and State of New York, have invented a new, original, and ornamental Design for Embroidered Textile Fabric, of which the following is a specification, reference being had to the accompanying drawing, forming part thereof.

The figure is a face view of an embroidered textile fabric, showing my new design.

I claim:

The ornamental design for an embroidered textile fabric, as shown.

In testimony whereof I have affixed my signature this 18th day of February, 1926.

GEORGE J. ABDELNOUR.
